SAFETY SWITCH

Joseph H. Schellman, Ridley Park, Pa., assignor
to Hetherington, Inc., Sharon Hill, Pa., a cor-
poration of Delaware

Application April 2, 1951, Serial No. 218,816

17 Claims. (Cl. 200—77)

1

The present invention relates to electric switches, particularly of the type which make instantaneous contact, as for example to operate mechanism on an airplane or the like.

A purpose of the invention is to provide protection against welding or freezing of electric contacts, particularly in the case of control mechanism.

A further purpose is to provide for completion of two sets of electric contacts in series in the forward motion of a plunger and provide for breaking both sets in retraction, and in any case for breaking one set in case the other will not break on account of welding.

A further purpose is to place one or more self-adjusting movable contacts on the plunger in series with the shorting contact closed by a hill and valley projection on the plunger.

A further purpose is to mount the self-adjusting movable contact or contacts on a self-adjusting movable contact carrier which has lost motion with respect to the plunger, preferably due to the action of a spring in urging the self-adjusting movable contact carrier against a shoulder on the plunger.

A further purpose is to provide a self-adjusting movable contact on a plunger which engages the fixed contact and which is electrically connected in a circuit by the shorting contact which closes against the self-adjusting movable contact or other contact in electrical connection with the self-adjusting movable contact.

A further purpose is to bring a plurality of electrically separate self-adjusting movable contacts forward on the self-adjusting movable contact carrier of a plunger into engagement respectively with fixed contacts, and then to interconnect the self-adjusting movable contacts while they are connected to the fixed contacts by movement of the shorting bar carrying the shorting contact under the action of a hill and valley projection on the plunger.

A further purpose is to bring a self-adjusting movable contact in lost motion relationship with the plunger into contact with a fixed contact and then by reverse motion of the shorting bar over the hill and valley projection to interconnect the self-adjusting movable contact while engaged with the fixed contact to a plurality of other fixed contacts inwardly extending into the path of the shorting contact.

A further purpose is to make fixed contact connection with the plunger itself, which is of electrically conducting material.

A further purpose is to extend a locating ear from the self-adjusting movable contact carrier

2

between fixed contacts to maintain the relationship of the self-adjusting movable contact or contacts to the fixed contacts.

A further purpose is to provide auxiliary contacts which will complete a circuit on further forward motion of the plunger when the circuit is not completed on initial forward motion.

A further purpose is to provide rearwardly directed fixed contacts which are engaged by self-adjusting movable contacts and forwardly directed fixed contacts which are engaged by the shorting bar, and to interconnect one of the rearwardly directed contacts with one of the forwardly directed contacts.

A further purpose is to provide a first self-adjusting movable carrier and self-adjusting movable contacts and a shorting bar, which together complete contacts in series on an initial forward motion of the plunger, and to provide an auxiliary self-adjusting movable carrier and contacts which complete the circuit on further forward motion of the plunger notwithstanding the failure of the shorting bar to operate.

A further purpose is to provide opposed plunger switches with a lost motion connection between them, having only sufficient freedom to permit one switch to operate at a time, so that in case of closing motion on one switch the other switch is forced open.

A further purpose is to provide a lever interconnection between the plungers of switches arranged side by side which will force open one switch when another switch is closed.

A further purpose is to make the lever interconnection universal in action so that a plurality of switches will interlock to permit the closing of one switch to force open an opposite switch.

Further purposes appear in the specification and in the claims.

In the drawings I have chosen to illustrate a few only of the numerous embodiments in which my invention may appear, selecting the forms shown from the standpoints of convenience in illustration, satisfactory operation and clear demonstration of the principles involved.

Figures 1 to 8 show the preferred embodiment.

Figure 1 is an axial section (through the axis of the plunger) of the preferred form, the switch being in open position.

Figure 2 is a view similar to Figure 1, showing the switch partially closed.

Figure 3 is a view similar to Figure 1, showing the switch fully closed.

Figure 4 is a section on the line 4—4 of Figure 1, the switch being open.

Figure 5 is a section on the line 5—5 of Figure 2.

Figure 6 is a bottom plan view of Figure 1.

Figure 7 is a bottom plan view of the self-adjusting movable contact carrier of Figures 1 to 6.

Figure 8 is a perspective of the shorting bar, omitting the shorting contact and springs.

Figures 9 to 15 inclusive show a variant embodiment of the switch of the invention.

Figure 9 is an axial section through the case on the line 9-9 of Figure 13, with the self-adjusting movable contact carrier and fixed contact block shown in elevation and the switch in open position.

Figure 10 is a section on the line 10-10 of Figure 13 showing the switch partially closed.

Figure 11 is a view similar to Figure 10 with the lower portion of the case shown in elevation and the switch fully closed.

Figure 12 is a section on the line 12-12 of Figure 9.

Figure 13 is a section on the line 13-13 of Figure 9.

Figure 14 is a bottom plan view of Figure 9.

Figure 15 is a bottom plan view of the self-adjusting movable contact carrier of Figures 9 to 13.

Figures 16 to 20 illustrate a further variation in the switch of the invention.

Figure 16 is an axial section through the switch of this variation, in open position.

Figure 17 is a section on the line 17-17 of Figure 16, in open position.

Figure 18 is a section on the line 18-18 of Figure 16.

Figure 19 is a bottom plan view of the fixed contact block of Figures 16 to 18.

Figure 20 is a top plan view of the main self-adjusting movable contact carrier and the auxiliary self-adjusting movable contact carrier of Figures 16 to 19.

Figure 21 is an axial section through the outer case of the preferred embodiment of interlock applied to the switches of the invention.

Figures 22 to 24 illustrate a further interlock embodiment.

Figure 22 is an axial section showing one of the switches in elevation.

Figure 23 is a section on the line 23-23 of Figure 22.

Figure 24 is a bottom plan view of Figure 22.

Figures 25 to 27 illustrate a further variation of interlock.

Figure 25 is an axial section in open position.

Figure 27 is a section on the line 27-27 of Figure 25.

Describing in illustration but not in limitation and referring to the drawings:

Switches of the instantaneous contact variety such as push button switches and instantaneous contact rocker and toggle switches are widely used, particularly in aircraft applications. Such switches find very important applications especially in aircraft, where they constitute the main actuating switches for trim tab circuits (trimmer ailerons), gun and rocket firing circuits, drop tank circuits and numerous other control and signal circuits. It will readily be understood that the proper functioning of such switches is critical both to the safety of the airplane or other equipment and to the proper performance of the machine.

Difficulty has been encountered, through the tendency of such switches to freeze or weld closed on making contact, or to fail to make contact.

Either condition may be serious or fatal in the operation of the airplane or other equipment.

By the present invention it is possible to assure the breaking of a vital circuit notwithstanding that one set of contacts may freeze or weld.

It is also possible by the present invention to close a circuit by forward movement of the plunger notwithstanding that one set of contacts may fail to close. The present invention also makes it possible to apply a counter dislodging force to break the connection of contacts which may have welded or frozen closed.

While the invention is believed to have its widest application in instantaneous contact aircraft switches, it will be understood that it can also be applied to switches employed in other applications and is by no means limited either to aircraft or to instantaneous switches.

Considering first the form of Figures 1 to 8 inclusive, I there illustrate a plunger switch having a suitable outer metallic case 30, desirably of circular cross section, having an externally threaded stem 31 of well known character which is intended to pass through and suitably thread in an opening 32 through a panel 33 (which may be the instrument panel of an airplane). The stem is held in place and the switch is positioned by opposed nuts 34 and 35 acting on a washer 36 against the outside of the panel.

The stem 31 has passing through the center a push button opening 37 which is provided with a forwardly directed shoulder 38. A push button or actuating member 40 passes through the opening 37 and has a shoulder 41 near its inner end 35 which engages against the shoulder 38 in the stem in retracted position and prevents dislodgment of the push button from the stem.

In the form of Figures 1 to 8 the push button is suitably of insulating material as shown, but it will be understood that it can be slightly modified to aid the grip and made of metal if desired, as shown in 40' in Figures 16 and 17.

The push button is desirably rigid with and effectively a part of switch plunger 42 which extends down the center of the switch as later explained. The plunger is preferably made of metal, and for the purpose of joining with the plastic push button is provided with a rear end boss 43 which is imbedded in the plastic and a slightly forward boss 44 which conforms to the interior cylindrical cross section of a spring recess 45 which extends inside the push button around the plunger.

Forwardly of the boss 44, the plunger has a uniform lost motion sliding portion 46 which is surrounded and engaged by a loose freely-longitudinally-movable self-adjusting movable contact carrier 47. The self-adjusting movable contact carrier is suitably recessed at 48 forwardly and the end of the recess engages a rearwardly directed shoulder 50 formed by a rim on the plunger which forwardly terminates the lost motion sliding portion 46.

Rearwardly directed from the self-adjusting movable contact carrier, immediately around the plunger, is a rim 51 on the self-adjusting movable contact carrier which guides the inside of a lost motion spring 52 in the spring recess 45 extending from the push button at the rearward end to the self-adjusting movable contact carrier at the forward end.

The self-adjusting movable contact carrier in this form is of electrical insulation material such as phenolic plastic, and has at circumferentially spaced points on its forward surfaces (suitably

diametrically opposite position), self-adjusting movable contacts 53 and 54 of any material having good electric conductivity, preferably silver. The self-adjusting movable contacts are desirably placed by imbedding in the plastic.

In line with the respective self-adjusting movable contacts and positioned forwardly of them are rearwardly directed fixed contacts 55 and 56 suitably provided with terminal ends 57 to permit direct solder connection to the ends. The terminal ends are desirably imbedded in a plastic or other suitable insulating block 58, secured in the forward open end of the casing 30. An insulating sleeve 60 on the inside of the casing surrounds the self-adjusting movable contact carrier and the rearwardly directed ends of the fixed contacts.

A locating ear 47' from the self-adjusting movable contact carrier of plastic extends down between fixed contacts 55 and 56 and guides the self-adjusting movable contact carrier against turning so that the self-adjusting movable contacts would not register with the fixed contacts.

The plunger has a hill and valley projection 61 located forwardly of the shoulder 50, and a shorting bar 62 of any well known character surrounds the plunger and rides over the hill and valley projection.

The shorting bar 62 desirably comprises a U-shaped metallic strip 63 (Figure 8) having an opening 64 in the center of the base of the U, large enough to pass over the hill and valley projection. The arms 65 of the U extend forwardly and in the inactive position engage an abutment surface 65' (Figure 3) on the insulating block 58, which limits the forward motion of the shorting bar and pushes the shorting bar over the hill and valley projection when the plunger moves forward. On the opposite sides of the plunger, generally straight spiral springs 66 extend across the shorting bar and are held inside the U of the shorting bar and in spring engagement with the plunger by ears 67 from the arms 65, which extend inwardly and restrict the ends of the springs as best seen in Figure 8.

Forwardly of the springs, the shorting bar has a transverse insulating plate 68 (Figure 2) provided with a hole 70 at the center, large enough to pass over the hill and valley projection, and held in place by ears 71 (Figure 8) from the arms 65 of the U, which engage at the corners of the insulating plate with interfitting projections on the insulating plate fitting in the recesses formed by ears 71.

On the side of the shorting bar, directed toward the self-adjusting movable contacts, a disc-like shorting contact 72 is located, secured to the shorting bar as by welding. The shorting contact is of any suitable contact material, such as silver. The radial extent of the shorting contact 72 and of the other parts of the shorting bar is limited so that they will not touch the fixed contacts as the shorting bar moves back and forth, but is great enough so that the shorting contact will engage, and in the form of Figures 1 to 8 will bridge, the self-adjusting movable contacts when the shorting bar moves rearwardly over the hill-and-valley projection.

At the forward end the plunger has a spring abutment or collar 73 and a spring stem 74 which engages inside a plunger retraction compression spring 75 in a spring well 76 in the insulating block 58. Retracting spring is engaged by the spring abutment at one end and by the bottom of

the well at the other end and is guided by the spring stem 74 inside the spring.

At the outside of the switch, ribs 77 of insulation suitably integral with the insulating block extend across the block between the fixed contact terminals.

In operation, when the user presses the push button to depress the plunger, the plunger starts from its rearward position with the shorting bar forward against the abutment 65' on the insulating block and the lost motion of the self-adjusting movable contact carrier taken up. The plunger and self-adjusting movable contact carrier move forward together as a unit to the position shown in Figure 2, at which position the self-adjusting movable contact or contacts on the self-adjusting movable contact carrier engages the fixed contact or contacts and to that extent completes the circuit. In the preferred embodiment, however, when the self-adjusting movable contacts engage the fixed contacts, the hill-and-valley projection has not yet moved far enough forward in the shorting bar to trip the shorting bar and make it move rearwardly against the self-adjusting movable contacts. On further forward motion of the plunger, as shown in Figure 3, however, the shorting bar is tripped as well known and moves rearwardly along the plunger over the hill-and-valley projection with a snap action, until the shorting contact engages the self-adjusting movable contacts, at which point the circuit is completed. Thus current flows from one fixed contact to the cooperating self-adjusting movable contact, to the shorting contact, to the other self-adjusting movable contact and thence to the other fixed contact. The self-adjusting movable contacts in this case complete the circuit between each fixed contact and the shorting contact.

When the pressure by the user on the plunger is relaxed and the plunger retracts under the action of the retracting spring and the self-adjusting movable lost motion spring, the plunger moves rearwardly while the shorting bar is held by the engagement of the shorting contact with the self-adjusting movable contacts. First, the hill-and-valley projection retracts through the shorting bar until the shorting contact is tripped and snaps in the forward direction over the hill-and-valley projection to the position of Figure 2. This snap action breaks the circuit and breaks any arc. On further retraction of the plunger, the lost motion between the self-adjusting movable contact carrier and the plunger is taken up until the self-adjusting movable contact carrier has engaged the rearwardly directed shoulder 50 on the plunger, after which the self-adjusting movable contact carrier and self-adjusting movable contacts move rearwardly with the plunger on further retraction to the position of Figure 1, breaking the electrical connection between the self-adjusting movable contacts and the fixed contacts.

In case either set of contacts welds or freezes when the circuit is made, the circuit can nevertheless be broken by the other set of contacts. Thus if the shorting contact welds or freezes at either side to one of the self-adjusting movable contacts, the retraction of the plunger will nevertheless break the circuit between the self-adjusting movable contact and the fixed contacts. On the other hand, if welding or freezing occurs between either of the fixed contacts, and the corresponding self-adjusting movable contact, the circuit is broken by the shorting contact

when the shorting bar moves forward on the hill-and-valley projection. This effect is made possible by the fact that the respective contacts are connected in series.

The form of Figures 1 to 8 employs a plurality of contacts completing a single circuit in series. In the form of Figures 9 to 15 which is generally similar, a plurality of contacts in series complete the circuit to serve different branches by connecting to a number of different terminals. In this case the self-adjusting movable contact carrier, which is generally similar to that already described, and mounted on a similar plunger, supports a single shelf-adjusting movable contact 53, which in forward position as shown in Figures 10 and 11 engages a single fixed contact 55' provided with a suitable terminal connection on the outside of the insulating block 58'.

The shorting bar in the form of Figures 9 to 15 is desirably the same as that of Figures 1 to 8. A plurality of L-shaped fixed contacts, in the present instance 78 and 80, are mounted in the insulating block 58' in insulated relation, and have inwardly directed ends 81, whose forward edge is at the same forward position as the forward edge of the self-adjusting movable contact when it engages fixed contact 55'. Contacts 78 and 80 are provided with suitable external terminals as shown. The locating ear 41² on the self-adjusting movable contact carrier extends into a position between two of the fixed contacts and guides thereon to prevent relative turning of the self-adjusting movable contact carrier as it moves back and forth. This locating ear, like the self-adjusting movable contact carrier, is of insulating material in this form.

In the form of Figures 9 to 15, a metallic contact 82 at the forward end around the plunger and retracting spring conforms to the shape of the spring well and through the retracting spring 75 makes electrical contact with the plunger (which is of electrically conducting material) and through the shorting bar springs makes electrical connection with the shorting contact.

In operation in this form, the self-adjusting movable contact carrier is fully rearward and the shorting bar fully forward so that the switch is open in Figure 9. The pressure of the finger on the push button moves the plunger forward until the self-adjusting movable contact 53 engages fixed contact 55', as shown in Figure 10. At that point the self-adjusting movable contact and self-adjusting movable contact carrier cease to move forward and lost motion is taken up as the plunger moves forward. In the position of Figure 10 the hill-and-valley projection has not yet moved far enough forward to trip the shorting bar and the shorting bar is in its forward or inactive position.

On further forward motion of the plunger, as in Figure 11, the hill-and-valley projection moves to the other side of the shorting bar springs and the shorting bar is tripped and moves rearwardly until the shorting contact engages the self-adjusting movable and the inwardly projecting ends 81 of fixed contacts 78 and 80.

At this point it will be observed that common circuit connections are made from separate branches represented by fixed contacts 78, 80 and 82 with fixed contact 55', the circuit connections in each case being completed through the shorting bar and the self-adjusting movable contact.

On retraction of the plunger, the shorting bar is first tripped to its inactive or forward position,

breaking the circuit between fixed contacts 78, 80 and 82 respectively and the self-adjusting movable contact. On further retraction of the plunger the lost motion between the self-adjusting movable contact carrier and the plunger having been taken up, the self-adjusting movable contact carrier and self-adjusting movable contact move rearwardly with the plunger, breaking the circuit between fixed contact 55' and the self-adjusting movable contact.

If either of the contact-making means welds or freezes, the other can break the circuit by retraction. Thus if any of the contacts made by the shorting bar welds or freezes, the circuit is nevertheless broken on retraction of the plunger by separation of the self-adjusting movable contact from fixed contact 55' (which will normally be connected to the source of power at the positive side in a direct current circuit). Likewise, if welding or freezing occurs between the self-adjusting movable contact and fixed contact 55', the circuit is nevertheless broken by the shorting contact. In both of the forms above described, the retracting spring will ordinarily be relatively weak while the lost motion spring will ordinarily be stronger.

In some cases it is desirable to have emergency contact making means as well as emergency contact breaking means.

In the form of Figures 16 to 20 inclusive, the plunger 42' has a pin 43' imbedded in the push button. An insulating bushing 60' is on the inside of the casing. A lost motion stem 46' extends forwardly and then joins a further forwardly extending reduced second lost motion stem 46², having a rearwardly directed shoulder 48'. A main self-adjusting movable contact carrier 83 surrounds the lost motion stem 46' and has a rearward skirt-like extension 84 which rides along it. Unlike the previous self-adjusting movable contact carriers, this self-adjusting movable contact carrier is metallic and electrically conducting and carries self-adjusting movable contacts 53' and 54', suitably at diametrically opposite positions. Extending across at the center, self-adjusting movable contact carrier 83 is recessed at 84' to form a cruciform arrangement and across this recess extends auxiliary self-adjusting movable contact carrier 85, which in its forwardmost position rests against rearwardly directed abutment 89'. Self-adjusting movable contact carrier 85 is also metallic and electrically conducting and has diametrically opposite contacts 86 and 87 which are disposed 90° from contacts 53' and 54'. An opening 88 in self-adjusting movable contact carrier 85 conforms in slidable relationship with lost motion stem 46². The auxiliary self-adjusting movable contact carrier is urged forwardly against abutment 89' by lost motion spring 90 which acts between a forward shoulder 91 on the plunger and the self-adjusting movable contact carrier around lost motion stem 46². For the purpose of getting the auxiliary self-adjusting movable contact carrier and lost motion spring in place, the plunger may be made up in several pieces, threaded or otherwise united as well known.

The rear edge of auxiliary self-adjusting movable contact carrier 85 forms a rearward abutment 92 which normally engages main self-adjusting movable contact carrier 83. The main self-adjusting movable contact carrier is urged against abutment 92 by lost motion spring 93 acting between washer 94 surrounding the plunger forward of the push button and the rear edge

of the self-adjusting movable contact carrier 83. Skirt 84 guides the spring.

Both of the self-adjusting movable contact carriers are diametrically within the case, and an insulating lining 60' at the rearward end and inside of the case prevents electrical contact with the case.

The shorting bar, 62' in the form of Figures 16 to 20, is slightly different from that previously shown, and employs a ring 95 large enough to move over the hill-and-valley projection, having an annular external recess 96 which receives a spiral garter tension spring 97 which pushes a ball 98 into a ball recess 100 at one portion of the circumference so that the ball rides the hill-and-valley projection rather than the spring directly. A shorting contact 72 suitably of silver, is mounted on the rearward face of the shorting bar and suitably is an annulus. The shorting bar is engaged by an abutment on the insulating block 58' which closes the forward end of the casing and inwardly insulates the casing wall from the shorting bar by a skirt.

The forward end of the plunger is inwardly recessed at 101 to receive a retraction compression spring 76' which extends from the bottom of the recess at one end to the bottom of spring well 75' in the insulating block 58'.

Provision is made for lost motion between the rearward and forward portions of the plunger by extending a stem 102 of the rearward portion into a recess 103 in the forward hill-and-valley portion. A lost motion compression spring 104 extends from a shoulder 105 on the rearward portion to a washer 106 around the stem 102 engaging the forward portion. The washer is, in inactive position of the switch, urged by the retracting spring against a shoulder 107 in a recess 108 of a fixed contact block 110 secured in the middle of the casing and positioned by the skirt portions of the insulations at the opposite ends.

The insulating block 110 supports a number of fixed contacts. A rearwardly directed fixed contact 111 cooperating with self-adjusting movable contact 53' and covering a segment less than 90° is electrically connected to an external terminal 112 which is insulated from the casing by bushing 113. The opposite self-adjusting movable contact 54' cooperates with rearwardly directed fixed contact 114 which suitably extends almost 180° and cooperates also in closed position with auxiliary self-adjusting movable contact 87. Fixed contact 114 is electrically connected as by metallic rivet 115 to a forwardly directed fixed contact 116 on the opposite side of the fixed contact block which also suitably covers slightly less than 180° as shown in Figure 19, and which cooperates with the shorting contact 72. Positioned 90° from fixed contact 111 and rearwardly directed is fixed contact 117 which is connected to an external terminal 118 and insulated from the case by bushing 120. Fixed contact 117 is electrically connected to forwardly directed fixed contact 121 as by rivet 122. Fixed contact 121 also desirably extends slightly less than 180° and cooperates with the shorting bar.

In operation of the form of Figures 16 to 20, when the user presses on the push button 40' and moves the plunger forward, the rearward portion of the plunger begins to move forward, carrying with it the main and auxiliary self-adjusting movable contact carriers, but the hill-and-valley projection does not move forward due to the lost motion at lost motion stem 102. Spring 104 is suitably weaker than spring 76' in the pre-

ferred embodiment. As the rearward portion of the plunger moves forward, self-adjusting movable contacts 53' and 54' make electrical connection respectively with rearwardly directed fixed contacts 111 and 114. Since contacts 114 and 116 are electrically connected by rivet 115, the electrically conducting self-adjusting movable contact carrier 83 has thus made electrical connection with fixed contacts 111, 114 and 116.

Further forward motion of the plunger takes up lost motion with self-adjusting movable contact carrier 84 and compresses plunger compressing spring 90. By this time the lost motion between the rearward and forward portions of the plunger has been taken up by compressing spring 104 and further forward motion of the plunger causes the hill-and-valley projection to move forward with the rearward portion of the plunger. This brings the ball 98 to the other side of the hill-and-valley projection and causes the shorting bar to snap rearwardly on the plunger, bringing the shorting contact into electrical connection with the forwardly directed fixed contacts 116 and 121. As a result contact 121 is connected to the other contacts and since it is electrically connected by rivet 122 with the body of contact 117, the circuit is completed from terminal 112 to terminal 118. In breaking the circuit the action is exactly like that of the other forms already described, the shorting bar first snapping forwardly to break connection between forward directed contacts 116 and 121 and then the self-adjusting movable contact carrier 83 moving rearwardly to the position shown in Figure 16. If the shorting contact becomes welded or frozen, self-adjusting movable contact carrier still breaks the circuit. If one of the self-adjusting movable contacts 53' or 54' becomes frozen or welded, the shorting bar still breaks the circuit.

During all of this operation the auxiliary self-adjusting movable contact carrier has been inactive. If, however, the shorting bar should fail to operate, for example due to breaking of its spring or clogging of its parts with dust or the like, it is still possible to complete the circuit by pushing the plunger still further forward until self-adjusting movable contacts 86 and 87 on auxiliary self-adjusting movable contact carrier 85 make electrical connection across from rearwardly directed fixed contact 114 to rearwardly directed fixed contact 117. In this instance an auxiliary circuit is made to replace the shorting bar circuit from fixed contact 111 to self-adjusting movable contact 53' through self-adjusting movable contact carrier 83 which is electrically conducting) self-adjusting movable contact 54', to fixed contact 114, to auxiliary self-adjusting movable contact 87, to auxiliary self-adjusting movable contact carrier 85 (which is electrically conducting), to auxiliary self-adjusting movable contact 86, to fixed contact 117.

In some instances it is not sufficient merely to provide auxiliary contacts for making and breaking the circuit, but is very desirable also to be able to exert a pushing action on the plunger to dislodge the plunger when it sticks. The forms of Figures 21 to 27 illustrate different ways in which this can be accomplished.

The form of Figure 21 is particularly suitable for trim tab switches or other switching installations where two switches move the same element in opposite directions or in opposite manner. In this form a frame 123 has opposed switch pockets 124 and 125 which receive plunger switches, which may be of any suitable char-

acter, whether prior art plunger switches or switches of the character shown therein, but are shown as being the switches of Figures 1 to 8 inclusive. One switch has an extension on its plunger through the rear, which carries an abutment 126, and on the other plunger carries a U-shaped socket 127 which receives the abutment. The plungers are preferably co-axial so that the forces are directly in line. The lost motion between the abutment and bottom of the socket is sufficient to close one switch, but insufficient to permit the other switch to close also. Accordingly, if the left hand switch in Figure 21 is closed and the lost motion is taken up, and the plunger of that switch sticks, the plunger can be dislodged by pressing on the push button 43 of the right hand switch, which exerts pressure from the socket 127 to the abutment 126. It will be evident that it is difficult to supply a substantial pulling force on the push buttons, but that a pushing force or tapping action can be exerted from the other switch in this manner.

In the form of Figures 22 to 24 the reverse action is exerted on the plungers by a lever. In this form a double switch housing 128 mounts two plunger switches 130 and 131, suitable of the character shown in Figures 1 to 8. Instead of the usual push button, hemispherical heads 132 are mounted on the plungers, and in retracted position the shoulders 41 on the heads engage in shoulders 38 of openings 52 in a mounting plate 133 extending across the housing. The mounting plate at the middle supports a pivot 134 on which a rocker 135 extending across and engaging the respective heads 132, is duly pivoted. An operating handle 136 extends through an opening 137 in the front of the switch, and permits the operator by rocking the handle to depress either one of the switches.

An insulating sleeve 138 surrounds the switches on the inside of the casing.

The fixed contacts of both switches are mounted on an insulating block 140 which holds the contacts in the relationship shown in Figures 1 to 8 inclusive. Each of the plungers has a forward extension 141 threaded on the end at 142 beyond the projection, and provided with a forward shoulder 73' which engages the rearward end of the retraction spring 76 in the spring well 75. The plunger extension passes through an opening 143 in the insulating block 140 and beyond the forward end of the block engages one end of an interlock lever 144 pivoted at 145 on a fulcrum 146 mounted on the block 140. There is only sufficient lost motion between the plungers and the interlock lever 144 to permit one switch to move to closed position at a time and as soon as one switch moves to closed position the opposite end of the interlock lever pushes rearwardly on the plunger of the other switch, thus exerting a positive dislodging force to reduce any weld or obstruction. Thus, if the functioning of a particular switch is impaired, the user can momentarily close the opposite switch of the pair and by doing so can correct the malfunctioning of the switch which is not properly operating.

The features shown in the form of Figures 22 to 24 are embodied in the form of Figures 25 to 27, which shows a four-switch group consisting of switches 147, 148, 150 and 151, each suitably like the construction of Figures 1 to 8 inclusive, mounted in an insulating casing 152 at 90° circumferential spacing. The outer fixed contacts extend up at 153 adjoining the insulat-

ing casing, while the inter fixed contacts 154 in this case are connected to a common terminal post 155, placing all of the switches in branches of the same circuit. A ball 156 at the face of the housing is supported by a threaded stud 157 in a threaded opening 158 of the cover 160. A switch operating rocker 161, suitably of insulation, has a socket 162 which makes universal joint mounting on the ball and has an annular lever flange 163 which engages the button heads of all the switches. The motion of the lever 161 can be confined to the four directions required to move the four switches by a cruciform slot in the panel as well known (not shown).

The stud 157 is extended and receives a universal joint spherical surface pivot bearing 164 which pivotally mounts an interlock plate 165 having an opening passing the stud and having fork ends 166 which engage around each plunger and the spring 52, between the push button head and the self-adjusting movable contact carrier.

In operation it will be evident that whenever the rocker 161 is rocked in the direction to close one of the switches, the corresponding end of the interlock plate is moved forwardly and the opposite end of the interlock plate is moved rearwardly, exerting a dislodging or retracting force on the interlock spring and through it on the plunger to dislodge the opposite switch. By this means any switch which sticks can readily be released. Also when one switch is closed, the interlock moves forward at that switch position and moves backward at the other switch positions, preventing the other switches from closing by engaging under their button head.

It will be evident that by the invention additional safety precautions are provided against damage to an airplane or other equipment through failure of control switching. These precautions take the form of provision for breaking a circuit in case an individual set of contacts stick, and also for closing a circuit in case an individual set of contacts fail and for releasing a sticking plunger.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention what I claim as new and desire to secure by Letters Patent is:

1. In a switch, a plunger, a self-adjusting movable contact carrier on the plunger, a contact mounted on the contact carrier, a fixed contact engaged by the contact on the contact carrier during forward movement, a hill-and-valley projection on the plunger, a shorting bar having spring means riding the hill-and-valley projection on the plunger and having a contact thereon, and an abutment engaged by the shorting bar during forward motion of the plunger and adapted to push the shorting bar over the hill-and-valley projection, the contact on the contact carrier, the shorting bar contact and the fixed contact making electrical connection when the plunger moves forward.

2. A switch according to claim 1, in which the contact on the contact carrier is engaged by both the fixed contact and the shorting bar contact 75 when the plunger moves forward.

3. A switch according to claim 1, in combination with a second fixed contact engaged by the shorting bar contact when the plunger moves forward.

4. A switch according to claim 1, in combination with a second contact on the contact carrier engaged by the shorting bar contact when the plunger moves forward and a second fixed contact engaged by the second contact on the contact carrier when the plunger moves forward.

5. A switch according to claim 1, in combination with a contact making electrical connection with the plunger.

6. A switch according to claim 1, in which the fixed contact extends radially inwardly into the path of motion of the contact carrier.

7. A switch according to claim 1, in which a plurality of fixed contacts extend radially inwardly into the path of motion of the contact carrier.

8. A switch according to claim 1, in combination with a further fixed contact arcuately spaced around the circumference from the aforesaid fixed contact and engaged by the contact on the contact carrier during forward movement, and an insulating locating ear extending forwardly from the contact carrier between the fixed contacts, there being electrical connection from the contact on the contact carrier to the further fixed contact including the contact carried by the shorting bar when the contact carrier engages the aforesaid fixed contact.

9. A switch according to claim 1, in which there are a plurality of circumferentially spaced contacts on the contact carrier electrically connected to one another, in combination with a second fixed contact engaged by one of the contacts on the contact carrier during forward movement, a third fixed contact in one position engaged by the contact on the shorting bar and electrically connected to the second fixed contact and a fourth fixed contact in one position engaged by the contact on the shorting bar and electrically connected to the third fixed contact by the contact of the shorting bar.

10. In a switch, a plunger, a self-adjusting movable contact carrier mounted on the plunger, over-travel means between the contact carrier and the plunger permitting the plunger to move further forward after the contact carrier is stopped, a contact mounted on the contact carrier, a fixed contact engaged by the contact on the contact carrier during forward movement, a hill-and-valley projection on the plunger, a shorting bar having spring means riding the hill-and-valley projection and having a contact thereon, and an abutment engaged by the shorting bar during forward motion of the plunger and adapted to push the shorting bar over the hill-and-valley projection, the fixed contact, the contact on the contact carrier and the shorting bar contact making electrical connection with one another when the plunger moves forward.

11. A switch according to claim 10, in combination with a second contact mounted on the contact carrier, and engaged by the shorting bar contact when the plunger moves forward.

12. A switch according to claim 10, in combination with a second contact mounted on the contact carrier and engaged by the shorting bar contact as the switch moves forward and a second fixed contact engaged by the second contact on the contact carrier when the plunger moves forward.

13. A switch according to claim 10, in combi-

nation with a second fixed contact engaged by the contact on the contact carrier during forward movement, a third fixed contact engaging the contact on the shorting bar when the plunger moves forward and electrically connected to the second fixed contact and a fourth fixed contact engaging the contact on the shorting bar when the plunger moves forward.

14. In a switch, a plunger having a rearwardly directed shoulder, a self-adjusting movable contact carrier surrounding the plunger and in one position engaging the shoulder, a spring resiliently urging the contact carrier against the shoulder, a contact mounted on the contact carrier, a hill-and-valley projection on the plunger, a shorting bar having spring means riding the hill-and-valley projection on the plunger and having a contact thereon, a fixed contact engaged by the contact on the contact carrier in forward motion, an abutment engaging the shorting bar as the plunger is moved forward, and a further contact engaged by the shorting bar when the shorting bar moves over the hill-and-valley projection, the contact on the contact carrier, the shorting bar contact, the fixed contact and the further contact making electrical connection when the plunger moves forward.

15. A switch according to claim 10, in which the aforesaid contact carrier is electrically conducting, a rearwardly directed shoulder on the plunger is engaged by the contact carrier in one position of the carrier and the aforesaid contact carrier is urged against the shoulder by a spring, in combination with a second forwardly directed contact on the aforesaid contact carrier, both contacts on the aforesaid contact carrier being forwardly directed and being electrically connected to the aforesaid contact carrier, a second electrically conducting contact carrier on the plunger angularly disposed at a different position from the first, contacts on the second contact carrier forwardly directed, the second contact carrier in one position engaging the aforesaid contact carrier, a spring urging the second contact carrier against the aforesaid contact carrier, a second rearwardly directed fixed contact in the path of movement of one of the contacts on the aforesaid contact carrier and also of one of the contacts on the second contact carrier, a third rearwardly directed fixed contact in the path of movement of another contact on the second contact carrier, a fourth fixed contact forwardly disposed into the path of movement of the contact on the shorting bar and electrically connected to the second fixed contact and a fifth fixed contact forwardly disposed in the path of movement of the contact on the shorting bar and electrically connected to the third fixed contact.

16. A switch according to claim 10, in which the aforesaid contact carrier is electrically conducting, a rearwardly directed shoulder on the plunger is engaged by the contact carrier in one position of the carrier and the aforesaid contact carrier is urged against the shoulder by a spring, in combination with a second forwardly directed contact on the aforesaid contact carrier, both contacts on the aforesaid contact carrier being forwardly directed and being electrically connected to the aforesaid contact carrier, a second electrically conducting contact carrier on the plunger angularly disposed at a different position from the first, contacts on the second contact carrier forwardly directed and normally extending further forward than the contacts on the

aforesaid contact carrier, the second contact carrier in one position engaging the aforesaid contact carrier, a spring urging the second contact carrier against the aforesaid contact carrier, a second rearwardly directed fixed contact in the path of movement of one of the contacts on the aforesaid contact carrier on forward travel and also of one of the contacts on the second contact carrier on less advanced forward travel, a third rearwardly directed fixed contact in the path of movement of another contact on the second contact carrier, a fourth fixed contact forwardly disposed in the path of movement of the contact on the shorting bar and electrically connected to the second fixed contact and a fifth fixed contact forwardly disposed in the path of movement of the contact on the shorting bar, and electrically connected to the third fixed contact.

17. A switch according to claim 10, in which the hill-and-valley projection is located on a plunger extension, the aforesaid contact carrier is electrically conducting, a rearwardly directed shoulder on the plunger is engaged by the contact carrier in one position of the carrier and the aforesaid contact carrier is urged against the shoulder by a spring, in combination with a lost motion connection between the plunger extension and the rest of the plunger including a spring tending to hold the hill-and-valley projection in forward position until the lost motion is taken up, a second forwardly directed contact on the aforesaid contact carrier, both contacts on the aforesaid contact carrier being forwardly directed and being electrically connected to the aforesaid contact carrier, a second electrically

conducting carrier on the plunger angularly disposed at a different position from the first, contacts on the second contact carrier forwardly directed, the second contact carrier in position engaging the aforesaid contact carrier, a spring urging the second contact carrier against the aforesaid contact carrier, a second rearwardly directed fixed contact in the path of movement of one of the contacts on the aforesaid contact carrier and also of one of the contacts on the second contact carrier, a third rearwardly directed first contact in the path of movement of another contact on the second contact carrier, a fourth fixed contact forwardly disposed in the path of movement on the contact on the shorting bar and electrically connected to the second fixed contact and a fifth fixed contact forwardly disposed in the path of movement of the contact on the shorting bar and electrically connected to the third fixed contact.

JOSEPH H. SCHELLMAN.
